UNITED STATES PATENT OFFICE.

THÉODORE STÜCKELBERGER, OF MONTMIRAIL, SWITZERLAND.

ELECTRIC CANDLE.

Application filed December 16, 1922. Serial No. 607,297.

To all whom it may concern:

Be it known that I, THÉODORE STÜCKELBERGER, a citizen of the Swiss Confederation, residing at Montmirail, Switzerland, ⁵ have invented certain new and useful Improvements in Electric Candles (for which I have filed an application for patent in Switzerland on the 11th of September, 1922), of which the following is a specification.

This invention relates to an electric candle which can be used for any purposes, such as illuminating rooms, bicycles or the like, in analogy with the battery lamps known ¹⁵ per se. The object of the invention differs from the battery lamps in so far that no special protecting casing is necessary, whereby however the pleasant appearance, the applicability and the illuminating power are ²⁰ not impaired.

The characteristic feature of the invention consists in that a closed cylindrical tube, which serves as a waterproof electrically insulating protecting sleeve, encloses absolutely airtightly a galvanic battery and carries at one of its ends an electric glow lamp bulb which is mounted in such a manner that without a casing and consequently without the aid of the contact device of a ²⁵ casing, the electric circuit is directly closed and interrupted by the glow lamp bulb itself in consequence of a rotation of the same in corresponding direction. The glow lamp bulb is protected by means of a transparent ³⁰ sleeve with reflector, this sleeve being mounted upon the candle.

In the accompanying drawing the object of the invention is shown in a form of construction by way of example, wherein:

Fig. 1 is a side elevation.

Fig. 2 a vertical section.

Fig. 3 shows the protecting sleeve with reflector seen from the side where it is slit.

Fig. 4 shows a diagram of connections.

With reference to the drawing, 1 designates the cylindrical tube which is preferably made from electrically insulating waterproof white and opaque material, for instance celluloid. In the tube 1 three dry ⁴⁵ cells 2 are superposed and connected in series (Fig. 4)—The negative pole of the one element is always connected with the positive pole of the other element by the wire 3.

The number, shape, size and arrangement

of the elements 2 can be different from those shown on the drawing as they depend on the dimensions of the candle.

Between the sides of the elements which face one another a disk 4 of celluloid is arranged and the free space between two adjacent elements is filled with an insulating mass, for instance cotton wool, spun glass or the like. The tube 1 is closed at the lower end by a cover 5 and at the upper end by a ⁶⁰ cover 6. Covers 5 and 6 are preferably made both of the same material as the tube 1. The end of tube 1 closed by the cover 5 is made tight by a filling mass 7 and the other end by a mass 8. The filling mass ⁶⁵ 7 or 8 consists of a waterproof electrically insulating material, for instance resin or the like.

In the filling 8 the Edison screw 9 is embedded into which the electric glow lamp ⁷⁰ bulb 10 is screwed. The one end of the insulated wire 19 is connected with the Edison screw 9. If the inner contact of the glow lamp bulb comes in contact with the carbon electrode 11 or with the positive pole ⁷⁵ 80 of the battery chain the circuit is closed and the incandescent lamp burns as the screw 9, owing to the connection by wire 19, represents the negative pole of the battery chain.

The projecting electrode 11 is surrounded by an insulating ring 4' with the object to permit of insulating the same with regard to the screw 9 and of separating the same from the filling mass 8 which is introduced ⁸⁵ in liquid state.

An annular disk 12 is positively connected with the glow lamp bulb 10. This disk has a downwardly directed handle 13 which is designated to prevent the rolling of the ⁹⁰ candle when being placed upon a table or similar surface. By displacement of the handle 13 the glow lamp bulb 10 is rotated and brought into or out of the contact position according to the direction in which it ⁹⁵ is moved. Upon the upper end of tube 1 the protecting sleeve 14 for the glow lamp bulb 10 is mounted. This protecting sleeve 14 is preferably made of elastic transparent material, for instance film, and it has a ¹⁰⁰ longitudinal slit 15. Owing to this slit 15 the protecting sleeve exerts upon the candle an elastic clamping action and a pressure. The handle 13 serves as support for the ¹⁰⁵ protecting sleeve 14 as regards displacement ¹¹⁰

- in longitudinal direction and when being turned it effects not only the rotation of the glow lamp bulb 10 but also of the protecting sleeve 14. Slit 15 has approximately 5 at its middle an enlargement 16 which is designed to receive the handle 13. In the protecting sleeve 14 a reflector 17 is arranged which extends only over one half of the circumference of the protecting sleeve. 10 The inwardly directed reflector consists of a tin foil, a mercury foil, an aluminium foil or of any convenient material and it is embedded in the mass of the protecting sleeve or mounted upon the outer wall of the 15 same. If the candle has to be used without reflector the protecting sleeve is merely turned upside down so that the half of the sleeve fitted with the reflector is in contact with the cylindrical tube 1. 20 The hand lever 13 of the annular disk 12 projects through the enlargement 16 of slit 15. If the protecting sleeve 14 is rotated by hand the hand lever 13 is drawn along and consequently the glow lamp bulb 10 is rotated so that it is lighted or extinguished.

Under normal conditions it is impossible that the glow lamp bulb is accidentally or automatically rotated as the rotation of the protecting sleeve 14, in consequence of its 30 elastic action, requires a certain expense of power.

Below the annular disk 12 a packing ring 18 is further arranged upon the glow lamp bulb or upon the socket of the same, said 35 packing ring 18 consisting of leather or rubber and being supported by the annular disk 12. If the glow lamp bulb 10 is brought into contact position this packing ring 18 is compressed and closes airtightly the hole through 40 which the screw part of the glow lamp bulb extends. Consequently the candle can be used also under water without any damage of the elements. The packing ring 18 will be used only if the protecting sleeve of the 45 candle, which is the cylindrical tube 1, is itself insulating and waterproof.

The costs of manufacturing the object of the invention are very low and certainly not higher than that of the batteries of the well 50 known pocket lamps. If the battery elements 2 are worn out they are thrown away together with the cylinder 1, the glow lamp bulb 10 with the annular disks 12, 18, the hand lever 13 and the protecting sleeve 14 55 being used in connection with a new battery.

I claim:—

1. Electric candle comprising in combination a closed cylindrical tube serving as waterproof electrically insulating protecting sleeve, a galvanic battery mounted in said tube, an electric glow lamp bulb mounted in the upper end of said tube in such a manner that without casing and without special contact devices the direct closing 60 and interrupting of the electric circuit is ef-

fected by the rotation of the glow lamp bulb, a transparent protecting sleeve mounted upon the upper end of said tube and a reflector in said protecting sleeve.

2. Electric candle comprising in combination a closed cylindrical tube serving as waterproof electrically insulating protecting sleeve, a galvanic battery airtightly mounted in said tube, an Edison screw mounted in the upper end of said tube, an electric glow lamp bulb mounted in said tube, an Edison screw in such a manner that without casing and without special contact devices the direct closing and interrupting of the electric circuit is effected by the rotation of the glow lamp bulb, a transparent protecting sleeve mounted upon the upper end of said tube and a reflector in said protecting sleeve.

3. Electric candle comprising in combination a closed cylindrical tube serving as waterproof electrically insulating protecting sleeve, a galvanic battery airtightly mounted in said tube, an Edison screw connected with one pole of the battery 85 mounted in the upper end of said tube, an electric glow lamp bulb mounted in said Edison screw, an inner contact of said glow lamp bulb adapted to be brought into contact with the other pole of the battery in such a manner that without casing and without special contact devices the direct closing and interrupting of the electric circuit is effected by the rotation of the glow lamp bulb, a transparent protecting sleeve mounted upon 90 the upper end of said tube and a reflector in said protecting sleeve.

4. Electric candle comprising in combination a closed cylindrical tube serving as waterproof electrically insulating protecting sleeve, a galvanic battery airtightly mounted in said tube, an Edison screw mounted in the upper end of said tube, an electric glow lamp bulb mounted in said Edison screw in such a manner that without casing and without special contact devices the direct closing and interrupting of the electric circuit is effected by the rotation of the glow lamp bulb, a transparent protecting sleeve mounted upon the upper end of said tube and a reflector in said protecting sleeve, an annular disk between said bulb and said screw, a packing ring upon said annular disk and a hand lever projecting from said annular disk serving to rotate said annular ring with the 105 lamp.

5. Electric candle comprising in combination a closed cylindrical tube serving as waterproof electrically insulating protecting sleeve, a galvanic battery airtightly mounted in said tube, an Edison screw mounted in the upper end of said tube, an electric glow lamp bulb mounted in said Edison screw in such a manner that without casing and without special contact devices the direct closing and 115

interrupting of the electric circuit is effected by the rotation of the glow lamp bulb, a transparent protecting sleeve mounted upon the upper end of said tube, a reflector in said protecting sleeve, an annular disk between said bulb and said screw, a hand lever projecting from said annular disk serving to rotate said annular ring with the lamp, and a packing ring directly connected with said 10 annular disk so that at the contact position of the glow lamp bulb this packing ring airtightly closes the contact device towards the outside for completing thus the insulating water-tight protecting cover of the 15 candle.

6. Electric candle comprising in combination a closed cylindrical tube serving as waterproof electrically insulating protecting sleeve, a galvanic battery airtightly mounted 20 in said tube, an electric glow lamp bulb mounted in the upper end of said tube in such a manner that without casing and without special contact devices the direct closing and interrupting of the electric 25 circuit is effected by the rotation of the glow lamp bulb, a transparent protecting sleeve mounted upon the upper end of said tube made from transparent elastic material being split in longitudinal 30 direction in order to produce a clamping action, said longitudinal slit being enlarged at the middle, and a reflector in said protecting sleeve.

7. Electric candle comprising in combination a closed cylindrical tube serving as waterproof electrically insulating protecting sleeve, a galvanic battery airtightly mounted 35 in said tube, an electric glow lamp bulb mounted in the upper end of said tube in such a manner that without casing and without special contact devices the direct closing and interrupting of the electric circuit is effected 40 by the rotation of the glow lamp bulb, a transparent protecting sleeve mounted upon the upper end of said tube, and a reflector in said protecting sleeve, inwardly directed and embedded in the mass of the protecting sleeve so that the metal foil of the reflector 45 is covered on both sides by the material of the sleeve.

8. Electric candle comprising in combination a closed cylindrical tube serving as waterproof electrically insulating protecting sleeve, a galvanic battery airtightly mounted 50 in said tube, an electric glow lamp bulb mounted in the upper end of said tube in such a manner that without casing and without

special contact devices the direct closing and interrupting of the electric circuit is effected by the rotation of the glow lamp bulb, a transparent protecting sleeve mounted upon the upper end of said tube, and a reflector in said protecting sleeve made of a metal foil extending only over one half of the length and over one half of the circumference of 60 the protecting sleeve so that the reflector can be put out of use by turning the protecting sleeve upside down.

9. Electric candle comprising in combination a closed cylindrical tube serving as 65 waterproof electrically insulating protecting sleeve, a galvanic battery airtightly mounted in said tube, an Edison screw mounted in the upper end of said tube, an electric glow lamp bulb mounted in said Edison screw in 70 such a manner that without casing and without special contact devices the direct closing and interrupting of the electric circuit is effected by the rotation of the glow lamp bulb, a transparent protecting sleeve mounted 75 upon the upper end of said tube and a reflector in said protecting sleeve, an annular disk between said bulb and said screw, a packing ring upon said annular disk and a hand lever projecting from said annular 80 disk serving to rotate said annular ring with the lamp, said hand lever projecting through the enlargement of the longitudinal slot of the protecting sleeve so that the said protecting sleeve is rotated with the glow lamp 85 bulb if the hand lever is being turned.

10. Electric candle comprising in combination a closed cylindrical tube serving as 90 waterproof electrically insulating protecting sleeve, a galvanic battery airtightly mounted 95 in said tube, an electric glow lamp bulb mounted in the upper end of said tube in such a manner that without casing and without special contact devices the direct closing and interrupting of the electric 100 circuit is effected by the rotation of the glow lamp bulb, a transparent protecting sleeve mounted upon the upper end of said tube and a reflector in said protecting sleeve, said hand lever being bent down at its upper end 105 so that it prevents the rolling of the handle if it is placed upon a table or other flat surface.

In testimony whereof I affix my signature in presence of two witnesses.
